Application September 12, 1934, Serial No. 743,698
 In Poland July 10, 1931

12 Claims. (Cl. 250—36)

My invention relates to improvements in radio systems and method of operation, and has for its main object to provide a new method and means for frequency multiplication.

In many cases, it is desirable to operate with a relatively low frequency in one part of a radio system, such as a transmitter or receiver and to use relatively higher frequencies in other parts of the system. This necessitates the provision of frequency multiplying means between the different portions of the system. An example of this occurs in single side-band transmission systems. The advantages of single side-band transmission with or without carrier suppression are well known. A substantial saving in transmitting power obtained through the suppression of the other side-band with or without the carrier frequency is effected.

A condition, however, encountered in transmission systems of this type is the fact that the suppression of the other side-band can be effectively carried out with low frequencies only, such as of the order of about twenty kilocycles for which filters with a sharp cut-off characteristic can be constructed. When starting with a low carrier frequency of the above order, it is necessary to increase the frequency to a higher carrier frequency by means of a frequency multiplication arrangement. In using the commonly known frequency multiplication systems such for example as one involving a non-linear characteristic vacuum tube for distorting the wave shape from which the desired high frequency is segregated by suitable filter means, great difficulties are encountered due to undesired cross modulation produced between the side-band frequencies of the modulated carrier. This results in substantial distortion and interference of the signals being transmitted.

Accordingly, an object of my invention is to provide a new method of and means for multiplying a given, and particularly a modulated, frequency without inducing interaction or cross modulation between the side-band frequencies.

Another object of the invention consists in providing an improved and simplified system for single side-band transmission with or without carrier frequency suppression and which is substantially free from distortion and similar objectionable interference inherent in systems of similar nature.

A further object of the invention consists in providing a new method of transmitting and reconstructing a carrier frequency for single side-band transmission systems to substantially reduce

fading and similar objectionable phenomena.

The invention has other objects in view which will appear hereinafter in a detailed description thereof in connection with the accompanying drawings in which:

Figures 1 and 2 are schematic diagrams illustrating the novel method and principle of frequency multiplication embodied in the invention.

Figure 3 shows one practical arrangement for carrying out the invention.

Figure 4 illustrates the response characteristic of a filter adapted for single side-band systems.

Figure 5 illustrates a modified circuit arrangement embodying the novel method of frequency multiplication as applied to single side-band transmission.

Figure 6 illustrates a modification of the circuit shown in Figures 3 and 5.

Figure 7 is a circuit diagram for receiving a single side-band transmission with auxiliary side frequencies for reconstructing the carrier frequency.

Figures 7a and 7b illustrate response characteristics explanatory of the operation of the circuit of Figure 7 and

Figure 8 illustrates a further modification of the system shown in Figure 3.

The novel method of frequency multiplication according to my invention involves the use of the heterodyne principle of producing combination frequencies by suitable modulating means through the use of vacuum tubes, rectifiers, etc., adapted to generate the sum and difference frequencies of two combining frequencies.

In Figure 1, I have shown a source for supplying a first frequency f_s , which in the present case is the carrier frequency in a radio transmission system. I have further shown an auxiliary frequency f_h supplied from another source for producing combination frequencies with f_s . For this purpose, the frequencies f_s and f_h are combined by means of modulator converters such as vacuum tube modulator amplifiers indicated schematically by M_1 and M_1' , thereby yielding the sum and difference frequencies $f_h + f_s$ and $f_h - f_s$ according to the well known trigonometrical equation

$$A_1 \sin w_1 t + A_2 \sin w_2 t =$$

$$\frac{A_1 A_2}{2} \cos (w_1 - w_2)t - \frac{A_1 A_2}{2} \cos (w_1 + w_2)t$$

in which $w_1 = 2\pi f_h$ and $w_2 = 2\pi f_s$.

In this manner the frequency f_s is transformed in the modulators M_1 and M_1' into its combination frequencies f_h+f_s and f_h-f_s of which the latter is segregated by suitable resonant means in the modulator M_1 and the former is segregated in the modulator M_1' . The thus obtained combination frequencies f_h+f_s and f_h-f_s are then in turn combined as shown in the second modulator M_2 thus yielding a combination frequency $f_s+f_h+f_s-f_h=2f_s$; that is, double the original or carrier frequency f_s . The double frequency $2f_s$ thus obtained is then combined with the auxiliary frequency f_h by means of a pair of further modulators M_3 and M_3' in a similar manner as previously described to produce side frequencies $2f_s+f_h$ and $2f_s-f_h$ yielding a further combination frequency equal to $4f_s$ produced by the modulator M_4 . In this manner, as will be understood from Fig. 1, any harmonic of the series $2^n f_s$ of the original or signalling frequency may be obtained and applied to a utilization circuit such as an amplifier transmission line or wireless antenna.

In Figure 2 I have shown a schematic arrangement similar to Figure 1 for the multiplication of a modulated carrier f_s specifically used in a single side-band transmission system for suppressing the side-band by means of a filter in the low frequency stage. For this purpose I have shown modulators m , m_1 , m_2 , m_3 , $m_4 \dots m_n$, illustrated by cross-hatched rectangles carrying the modulated frequency currents, while the modulators M_1 , M_1' , M_2 , M_3 , $M_4 \dots M_n$ are similar to the arrangement as shown in Figure 1 and carry unmodulated currents only.

By separately multiplying a modulated and unmodulated carrier, it is possible to combine modulated and unmodulated side-bands or frequencies in the respective multiplication stages, thus further eliminating mutual interferences such as cross-modulation or the like.

The modulated currents such as speech currents supplied from a microphone are conducted over the line 1 to the modulator m which is furthermore supplied with the frequency f_s . In this manner a modulated carrier is obtained which is combined in a further modulator m_1 with the auxiliary frequency f_h , thus yielding modulated intermediary frequencies f_s-f_h and f_s+f_h . At this stage, one of the side-bands may be suppressed, such as by means of a sharp cut-off filter having a characteristic as shown in Figure 4. At the same time, the carrier may also be suppressed by the proper design of the filter to encompass both one side-band and the carrier frequency as is understood. The modulating intermediary frequency f_s-f_h is then combined by means of a further modulator with an unmodulated intermediary frequency f_s+f_h supplied from the modulator M_1' as shown. In this manner, a modulated frequency $2f_s$ is obtained which in turn is combined by means of a further modulator m_3 with the auxiliary frequency f_h yielding a second intermediary modulated frequency $2f_s-f_h$, which latter is in its turn combined in a further modulator m_4 with the unmodulated second intermediary $2f_s+f_h$ supplied from the modulator M_3' , thus yielding a modulated frequency $4f_s$. In this manner, the process may be continued and a pair of final frequencies $2^n f_s$, one being modulated and one being unmodulated, obtained which may be combined in a common output for suppression of the carrier or, if the carrier has been previously suppressed, for restoration of the carrier in the common out-

put circuit connected to the terminals a and b . In this manner a final output frequency is obtained from the initial frequency f_s without distortion due to interference or interaction of the side-bands.

Referring to Figure 3, I have shown at 1, an audio-transformer for applying modulating currents such as obtained from a microphone to the amplifier 2. The amplified speech currents serve to modulate the initial or carrier frequency f_s supplied from a suitable source 16 to the power amplifier 3 by means of a high frequency transformer 4. The modulation shown is the well known anode current or Heising modulation. For this purpose the output of the amplifier tube is 15 directly connected to the anode of the power amplifier tube 3 whereby the high frequency currents in the output of the tube are modulated in accordance with the low frequency or modulating currents. From the output of tube 3, the 20 modulated high frequency f_s is applied to the input of a modulator amplifier or frequency converter tube 6 through transformer 5. In addition currents of the auxiliary frequency f_h produced by a generator 17 are applied to the modulator amplifier tube 6 as shown, resulting in the production of combination intermediary frequencies in the output of tube 6 of which the component f_s-f_h is segregated by means of a filter F which may have a characteristic as shown 30 in Figure 4 and may be designed to simultaneously suppress the carrier frequency as pointed out before. The thus obtained modulated first intermediary frequency is then applied to a further modulating tube 7 for combination with the 35 unmodulated intermediary frequency f_s+f_h supplied from the tube 9 of the unmodulated multiplier system to the anode of the tube 7 in Heising modulation arrangement.

The unmodulated intermediary frequencies are 40 produced by means of a pair of modulator-converter tubes 8 and 12 with input circuits supplied with the carrier frequency f_s through transformers 10 and 11, respectively, and with the frequency f_h directly applied to the input circuits of tubes 8 and 12 as shown. In this manner combination frequencies f_s+f_h and f_s-f_h are produced in the output circuits of tubes 8 and 12, respectively, of which the former is segregated in the output of tube 8 and the latter is 50 segregated in the output of tube 12 by suitable resonant means. The single intermediaries thus obtained are then applied through transformers 14 and 15, respectively, to the input of a pair of further tubes 9 and 13 whose anodes are connected for mutual modulation producing an unmodulated frequency $2f_s$ in their common output circuits connected through transformers 18 and 19 with the anode circuits of tubes 9 and 13, respectively. The modulated and unmodulated double frequency $2f_s$ thus obtained may be further mutually combined with the auxiliary frequency f_h in a similar manner to produce any desired multiple according to the series $2^n f_s$ as explained in connection with the schematic showing in Figure 2. 20 and 21 are coupling coils connecting the output of tubes 1 and 9 to a common output circuit carrying the double carrier frequency $2f_s$.

Figure 5 shows a modification of the circuit of Fig. 3 using a return or reflex arrangement from 70 a stage carrying a multiplied frequency to the input circuit of the initial frequency current resulting in a great simplification of the circuit. As shown, an audio-transformer 1 controls the speech amplifying tube 2 serving to modulate the 75

power amplifier 3 controlled by carrier frequency f_s . The modulated carrier is applied to the input of a modulator amplifier 6 which is also controlled by the auxiliary frequency f_h , thus yielding a one side-band modulated intermediary frequency $f_s - f_h$ by the further use of a suitable filter in a manner similar to that described in connection with Fig. 3. This latter is applied to the input of a further modulator tube 7 together with a non-modulated intermediary frequency $f_s + f_h$ supplied through a transformer 32 from the unmodulated carrier multiplication system. In this manner a modulated double carrier frequency $2f_s$ is obtained in the output of the tube 7 which is applied to the input of a further modulator amplifier tube 24 together with the auxiliary f_h resulting in a combination frequency $2f_s - f_h$ in the output of tube 24, which latter is in turn applied to the input of modulator amplifier 35 together with a non-modulated second intermediary frequency $2f_s + f_h$ supplied through transformer 29 from the unmodulated carrier system. In this manner, a modulated four-fold carrier $4f_s$ is secured in the output of tube 35 which by means of a transformer 36 may be combined with the non-modulated carrier $4f_s$ as shown supplied by the transformer 33 either for suppressing or restoring the carrier.

The non-modulated multiplication system comprises a first modulator tube 26 having its input controlled by both carrier frequency f_s and auxiliary frequency f_h , thus yielding two combination frequencies $f_s - f_h$ and $f_s + f_h$ which are both segregated by means of resonant circuits inserted in the output circuit of the tube and in turn combined in the input of a modulator tube 37 through coupling transformers 38 and 31 respectively. The resonant circuit carrying the frequency $f_s + f_h$ is furthermore coupled to the input of the tube 7 through transformer 32 as described before, to combine with the signal modulated intermediary $f_s - f_h$ for securing a modulated carrier $2f_s$ in the output of the tube 7. By combination of the intermediary frequency $f_s - f_h$ and $f_s + f_h$ by tube 37, a non-modulated double carrier frequency is secured in the output of the tube 37 which is returned or reflexed through transformers 34 and 34' to the input of the first modulator tube 26, thus combining with the auxiliary frequency f_h and producing further intermediate frequencies $2f_s - f_h$ and $2f_s + f_h$ in the output circuit of the tube 26, which are segregated by means of suitable resonant circuits as shown and applied through transformers 27 and 28, respectively, to the input of a modulator tube 38 for combination to yield a four-fold unmodulated carrier $4f_s$ in its output circuit which as described may be combined with the modulated four-fold carrier as shown. The intermediate frequency $2f_s + f_h$ is furthermore applied through transformer 29 to the input of the tube 35 for combination with the signal modulated intermediary frequency $2f_s - f_h$ as described hereinbefore. Otherwise the circuit and its operation is similar to that described in connection with Figure 3.

Figure 6 shows a circuit arrangement similar to Figure 5 for multiplication of the initial frequency to its sixteenth harmonic. In place of vacuum tube modulators for changing of the frequency, I have shown rectifiers, such as dry rectifiers or crystal rectifiers or the like arranged in a well known bridge circuit. In this manner

the entire circuit is greatly simplified and both the installation and maintenance costs greatly reduced. As is obvious, the generators 16 and 17 for the carrier frequency and the auxiliary frequency in this case must be designed for increased power or provided with suitable amplifiers. The circuit according to Figure 6 also utilizes the return or reflex principle as will be described in detail.

This circuit also substantially comprises a first system for multiplying the signal modulated carrier and a second system for multiplying the unmodulated or pure carrier and mutual circuit connections for combining modulated intermediary frequencies with unmodulated intermediary frequencies in a manner similar as described before to secure a final multiplied output frequency of a desired order free from distortion and similar effects inherent in systems heretofore known in the art.

Referring to the circuit arrangement of Figure 6, I have shown an input transformer 1 for applying the modulating, such as audio frequency currents supplied from a microphone or the like to a first modulating circuit 40 including a rectifier arrangement 41 comprising four rectifier elements such as dry or contact rectifiers connected in the well-known bridge circuit as shown. The circuit 40 furthermore is supplied with carrier frequency currents applied through transformer 45 from a circuit including the carrier frequency generator 16. In this manner a modulated carrier $f_s(m)$ is obtained and applied to an intermediate or filter circuit 42 of known design. From the circuit 42 the modulated carrier is applied to a further modulating circuit 43 including a rectifier arrangement 44 and supplied with auxiliary frequency currents supplied through transformer 70 from a circuit including the auxiliary frequency generator 17. In this manner a first intermediary signal modulated frequency is obtained of which one side-band (such as $f_s + f_h$ in the example shown) with or without the carrier may be suppressed such as by means of a suitable filter 46 as shown. This frequency is then applied to a modulating circuit 47 including a rectifier arrangement 48 and also carrying currents of the unmodulated intermediary frequency $f_s + f_h$ supplied from the unmodulated multiplication system through transformer 84. In this manner a multiple modulated carrier frequency $2f_s(m)$ is produced in the circuit 47 and its associate filter circuit 49. The frequency $2f_s(m)$ is then applied to the modulation circuit 50 including a rectifying arrangement 51 and also carrying currents of the auxiliary frequency f_h applied through transformer 71 connected in the auxiliary frequency circuit of the generator 17. The resulting combination frequency $2f_s - f_h(m)$ after passing through intermediate resonant circuit 53 is applied to a further modulation circuit 54 including a rectifying arrangement 55 and also carrying currents of the second unmodulated intermediary frequency $2f_s + f_h$ supplied from the unmodulated multiplying circuit through transformer 98. The resulting modulated carrier $4f_s(m)$ after passing through intermediate circuit 56 is in its turn applied to the modulating circuit 57 including a rectifying arrangement 58 and carrying currents of the auxiliary frequency f_h applied through transformer 72 from the circuit of the auxiliary generator 17. The resulting intermediary frequency $4f_s - f_h(m)$ after passing through an interme-

diary circuit 59 is then combined in circuit 60 including rectifying arrangement 61 with a non-modulated intermediary $4f_s + f_h$ supplied from the unmodulated multiplier through transformer 81 as shown. In this manner a modulated frequency $8f_s(m)$ is obtained, which after passing through intermediary circuit 62 is combined in a further modulation circuit 63 including a rectifying arrangement 64 with the auxiliary frequency f_h applied to the circuit through transformer 73 from the circuit of the auxiliary generator 17. The resulting modulated intermediary frequency $8f_s - f_h(m)$ after passing through intermediate circuit 65 is then combined in the modulation circuit 66 including rectifying arrangement 67 with the unmodulated intermediary $8f_s + f_h$ supplied from the unmodulated multiplier through transformer 95. From this there results a final modulated carrier $16f_s(m)$ applied to the

20

$$A_1 \sin w_1 t + A_2 \sin w_2 t = \frac{A_1 A_2}{2} \cos (w_1 - w_2)t - \frac{A_1 A_2}{2} \cos (w_1 + w_2)t$$

intermediate circuit 68 and which may be combined with the unmodulated carrier $16f_s$ produced by the unmodulated multiplier for either sup-

pression or restoration of the carrier as described before in a common output circuit to be connected to terminals *a* and *b*.
The unmodulated carrier multiplier is comprised of a first modulator circuit 78' including a rectifier arrangement 83' and supplied with the carrier frequency f_s through transformer 78 and with the auxiliary frequency f_h through transformer 74. The resulting combination frequencies $f_s + f_h$ and $f_s - f_h$ are segregated by means of intermediary circuits coupled through transformers 83 and 82', respectively, and combined in a modulating circuit 87 including a rectifying arrangement 88, thus yielding a frequency $2f_s$ in the associated intermediate circuit 90. The frequency $2f_s$ is then applied from the circuit 90 to a modulating circuit 90' including a rectifying arrangement 82 and also carrying currents of the auxiliary frequency f_h supplied through transformer 75 connected in the circuit of the auxiliary generator 17. The resulting combination frequencies $2f_s + f_h$ and $2f_s - f_h$ are segregated by means of intermediate resonant circuits coupled through transformers 92 and 96, respectively, and then combined in a modulation circuit 102 including a rectifying arrangement 103.

The resulting frequency $4f_s$ produced in the circuit 102 is returned or fed back in a reflex arrangement to the first modulation circuit 78' through transformers 104 and 105 where it is combined with the auxiliary frequency f_h , yielding intermediate frequencies $4f_s + f_h$ and $4f_s - f_h$ which are segregated by means of resonant intermediate circuits coupled to the circuit 78' through transformers 80 and 79, respectively. The intermediate frequencies $4f_s + f_h$ and $4f_s - f_h$ are then in turn combined in a modulation circuit 85 including a rectifying arrangement 86, thus yielding an unmodulated frequency $8f_s$ in the intermediate circuit 88 which in its turn is applied to the modulation circuit 90' through transformer 89' and combined therein with the auxiliary frequency f_h resulting in intermediate frequencies $8f_s + f_h$ and $8f_s - f_h$ which are segregated by means of intermediate circuits coupled to the transformers 94 and 93 and in their turn combined in a modulation circuit 100 including a rectifying arrangement 101, thus resulting in an unmodu-

lated frequency $16f_s$ in the intermediate circuit 100' which may be combined with the signal modulated frequency $16f_s$ as described.

In the arrangements according to Figures 5, 6 and 8, the desired beat or combination frequencies are segregated by means of resonant circuits. It is understood that any other segregating means or filters such as piezo crystals or the like with or without associated amplifiers may be provided for this purpose. It is furthermore understood that the reflex arrangement may be employed repeatedly, resulting in a further simplification of the circuit arrangement as is obvious.

An arrangement as shown in Figure 6 using rectifiers such as dry rectifiers, diodes, etc., has the great advantage that the modulation of the frequency f_s by the frequency f_h or its harmonics $2f_h f_s$ is linear; that is, the modulation conforms a general to the formula:

$$A_1 \sin w_1 t + A_2 \sin w_2 t = \frac{A_1 A_2}{2} \cos (w_1 - w_2)t - \frac{A_1 A_2}{2} \cos (w_1 + w_2)t$$

When vacuum tubes are used for the transposing of the frequencies with non-linear characteristics, the modulation conforms to the formula:

$$A_1 \sin w_1 t + A_2 \sin w_2 t = A_1 A_2 \cos (w_1 + w_2)t + A_1^2 \sin 2w_1 t + A_2^2 \sin 2w_2 t$$

From the last two members of the formula, it is seen that frequencies $2w_1 t$ and $2w_2 t$ are produced and in addition there will be higher harmonics of these frequencies which may cause interference and distortion of the signals being transmitted. The circuit according to Figure 6 is free from this disadvantage as already pointed out.

The arrangements according to Figures 2, 3, 5 and 6 can be further simplified where it is required to suppress one side-band and the carrier frequency. A simplified arrangement of this is shown by Figure 8 which merely differs from Figure 2 by the employment of harmonic frequencies of the auxiliary generator 17 such as the harmonic $2f_h$ used for beating with the modulated multiplied frequency $2f_s$ as shown, otherwise the circuit is similar in design and function to previous circuits as will be understood.

Referring to Figure 7, this shows a receiving system especially adapted therewith in connection with the invention and for communication with a single side-band and elimination of the carrier frequency. As is well known in systems of this type, means must be provided at the receiver for restoring the carrier necessary for reproducing the original signals.

In order to restore the carrier at the receiver in accordance with a further feature of the invention, additional side-bands or frequencies called "pilot" bands or frequencies are radiated from the transmitter. Thus for instance, the transmitter 60 may radiate a side-band produced from the modulation by a signalling frequency comprising a band of 30 to 4000 cycles with one side-band and the carrier being suppressed by any suitable means known in the art. In addition to this single side-band, two further side-bands or side frequencies are produced, for instance, by modulation according to a single not outside of the regular modulation band such as of 6000 cycles in the above example. Such "pilot" bands 65 or frequencies may easily be obtained by modulating the carrier in the final stage with a frequency of 6000 cycles and combining it with the modulated frequency in such a manner that the carrier itself is suppressed. Any suitable means known 75

in the art may be provided for this purpose, such as a balanced modulator and the like. Thus, two "pilot" frequencies or side-bands are obtained produced by the oscillations of 6000 cycles and a single modulated side-band produced by the signalling modulation and comprising 30 to 4000 cycles.

At the receiver the modulated side-band of 30 to 4000 cycles is received by a suitable filter F_2 having a response characteristic as shown in Figure 7b and applied either directly or through any suitable frequency changing means to the detector tube 116 for reception by a translating means such as loud speaker 115 with interposed amplifier well known in the art. The side frequencies produced by the oscillations of 6000 cycles are passed through filter F_1 having a response characteristic as shown in Figure 7a, and applied to a frequency doubling tube 111 or any other arrangement for doubling the frequency. In this manner the carrier wave of double frequency is restored in accordance with the equation:

$$[\cos(w-p)t - (w+p)t]^2 = \cos 2wt + \dots$$

This "pilot" frequency is then utilized for controlling an oscillator 112 having a frequency of

$$\frac{2wt}{2} = wt.$$

The frequency of the oscillator is applied to the detector tube 116, thus restoring the original carrier frequency for de-modulation and reception of the signal. In place of a single pilot frequency, such as 6000 cycles as in the example given, it is understood that a band of "pilot" frequencies may be provided and transmitted.

The above method of transmitting the carrier frequencies by means of its side-bands involves the great advantage of reducing the effects produced by fading, especially so-called selective fadings. The arrangement according to Fig. 7 may be furthermore modified by doubling the single modulated side-band passed through the filter F_2 by means of a frequency doubling arrangement such as of the type described hereinbefore and shown for instance by Fig. 3, and then to combine the doubled carrier frequency produced by the frequency doubling tube 111. In the latter case an additional auxiliary oscillator will be necessary as shown at f_h . I have furthermore shown at 110 an input amplifier and an antenna 113 with ground connection 114.

While the invention has been described with specific reference to the showing of the drawings, I desire it to be understood that various modifications may be made and that no limitations upon the invention are intended short of its broad and underlying spirit as expressed in the appended claims.

I claim:

1. The method of frequency multiplication consisting in combining a fundamental frequency wave with an auxiliary frequency wave to derive sum and difference combination frequency waves, combining said combination frequency waves to derive a further combination frequency wave therefrom equal to the second harmonic of said fundamental frequency wave, combining said second harmonic frequency wave with said auxiliary frequency wave to derive secondary sum and difference combination frequency waves therefrom, and combining said secondary combination frequency waves to produce a further combination frequency wave equal to four times the fre-

quency of said fundamental frequency wave and successively continuing the process until obtaining a final desired harmonic frequency wave of the order 2^n of the fundamental frequency.

2. The method of frequency multiplication consisting in combining a fundamental signal modulated carrier frequency wave with an auxiliary frequency wave to derive therefrom sum and difference combination frequency waves, producing similar combination sum and difference frequency waves from an unmodulated fundamental carrier frequency wave and said auxiliary frequency wave, and combining a combination frequency wave derived from the modulated carrier with a combination frequency wave derived from the unmodulated carrier to produce a modulated second harmonic of said carrier frequency wave.

3. The method of frequency multiplication consisting in beating a fundamental frequency signal modulated wave with an auxiliary frequency wave to derive therefrom sum and difference combination frequency waves, producing similar sum and difference combination frequency waves by beating an unmodulated fundamental wave of the same frequency as said fundamental signal modulated wave together with said auxiliary frequency wave, combining a combination frequency wave derived from said modulated fundamental frequency wave with a combination frequency wave derived from said unmodulated fundamental frequency to produce a modulated second harmonic of said fundamental frequency wave, producing a second harmonic of said unmodulated fundamental frequency wave, combining said second harmonic modulated fundamental frequency wave with said auxiliary frequency wave to derive secondary sum and difference combination frequency waves therefrom, producing similar secondary combination frequency waves by beating together said second harmonic unmodulated carrier frequency wave and said auxiliary frequency wave and combining a secondary combination frequency wave derived from said modulated second harmonic wave with a combination frequency derived from said unmodulated second harmonic wave to produce therefrom a modulated fourth harmonic of said fundamental frequency wave and continuing the process by producing further successive harmonics of said unmodulated fundamental frequency wave of like order supplied by said first said auxiliary frequency wave to derive combination frequency waves of the respective orders and combining said fourth harmonic modulated carrier wave with said auxiliary frequency wave and beating a resultant combination frequency wave with a corresponding combination frequency wave of like harmonic order of the unmodulated fundamental frequency wave to produce an 8th harmonic modulated wave of said fundamental frequency wave and analogously continuing the process until obtaining a desired modulated harmonic wave of the 2^n th order of said fundamental frequency wave.

4. The method of frequency multiplication as claimed in claim 3 in which said further harmonics of said unmodulated carrier frequency wave are produced by combining combination frequency waves derived therefrom by beating with said auxiliary frequency wave.

5. In a method of frequency multiplication as claimed in claim 3 including suppressing the carrier frequency component of the initial fundamental modulated carrier frequency wave and re-

introducing a carrier in the final stage obtained from multiplication of the unmodulated initial carrier wave frequency wave having the frequency necessary for said re-introduction to produce an output signal with a carrier component.

5. The method of frequency multiplication as claimed in claim 3 including suppressing one side-band of the initial fundamental modulated carrier frequency wave and suppressing the carrier frequency component in the final stage by combination with the multiplied unmodulated carrier wave having the same frequency as said carrier frequency.

6. The method of frequency multiplication as claimed in claim 3 including suppressing one side-band of the initial fundamental modulated carrier frequency wave and suppressing the carrier frequency component in the final stage by combination with the multiplied unmodulated carrier wave having the same frequency as said carrier frequency.

7. A frequency changing system comprising a source for producing a fundamental carrier frequency wave, a further source for producing an auxiliary frequency wave, means for combining said frequency waves to derive sum and difference combination frequency waves, further means for beating said combination frequency waves to derive a second harmonic of said fundamental frequency wave, and means for beating said harmonic frequency wave with said auxiliary frequency wave and beating resultant combination frequency waves to produce the fourth harmonic wave of the fundamental frequency wave and continuing the process of producing harmonic waves by beating with said auxiliary frequency wave and beating together resultant combination frequency waves substantially as described until obtaining a final desired harmonic wave of the 2th order of the said fundamental frequency wave.

8. A frequency changing system comprising a source for producing a fundamental carrier frequency wave, a further source for producing an auxiliary frequency wave, a first mixing circuit for combining said carrier frequency wave and said auxiliary frequency wave to derive sum and difference combination frequency waves, a second mixing circuit for combining said combination frequency waves to derive a second harmonic beat frequency wave of said fundamental, a third mixing circuit for beating said second harmonic frequency wave with said auxiliary frequency wave to derive secondary combination frequency waves, a fourth mixing circuit for combining said secondary combination frequency waves to derive therefrom a fourth harmonic wave of said fundamental, and further mixing circuits for producing higher harmonics of said fundamental frequency according to the series 2th until obtaining a desired fourth final harmonic frequency wave of desired order.

9. In a frequency changing system as claimed in claim 7, including means for feeding currents from a circuit carrying a wave of higher harmonic order to a circuit carrying a wave of lower harmonic order for producing combination frequencies between said currents and said auxiliary frequency wave in the mixing circuit for said lower harmonic frequency wave.

10. A frequency changing system comprising a source for producing a fundamental carrier frequency wave; means for modulating said carrier frequency in accordance with signal variations; a source for producing an auxiliary frequency wave; means for deriving an unmodu-

lated component of said carrier frequency wave; a first multiplication system for increasing said unmodulated carrier component comprising first heterodyning means for combining one unmodulated carrier with said auxiliary frequency wave to derive a combination frequency wave further heterodyning means for combining said combination frequency wave to derive a second harmonic carrier frequency wave, further heterodyning means for combining said second harmonic carrier frequency wave with said auxiliary frequency wave for producing combination frequency wave, means for heterodyning said latter combination frequency wave to produce a fourth harmonic of said carrier frequency wave, and means for alternately heterodyning harmonic frequency wave of said carrier with said auxiliary frequency wave and for mutually heterodyning the resultant combination frequency wave to produce a final desired harmonic of the 2th order of said unmodulated carrier frequency wave; and a second multiplication system for increasing said modulated carrier component comprising first mixing means for combining the modulated fundamental carrier frequency wave with said auxiliary frequency wave to derive combination frequency wave; further mixing means for combining one of the latter combination frequency wave with a combination frequency wave of like order of said unmodulated carrier component supplied by said first multiplication system to produce a modulated second harmonic carrier frequency wave; additional mixing means for combining said modulated second harmonic carrier frequency wave with said auxiliary frequency wave to derive combination frequency wave therefrom; further mixing means for combining one of said latter combination frequency wave with a corresponding combination frequency wave of like order supplied by said first multiplication system for producing a modulated fourth harmonic carrier frequency wave; and additional means for alternately heterodyning modulated harmonics of said carrier frequency wave with said auxiliary frequency wave and heterodyning resultant combination frequency wave of the modulated carrier frequency wave with a corresponding combination frequency wave of like order of the unmodulated carrier frequency wave supplied by said first multiplication system to secure a final modulated carrier of the 2th order of the fundamental carrier frequency wave.

11. A frequency changing system as described in claim 10 for single side-band transmission comprising means for suppressing one side-band of said modulated carrier in the fundamental stage.

12. In a frequency changing system for use in single side-band transmission system as claimed in claim 10 including means for suppressing one side-band and the carrier frequency of said modulated carrier component in the fundamental stage, and means for re-introducing the carrier in the final stage supplied by the first multiplication system for the unmodulated carrier component.
